UNITED STATES PATENT OFFICE.

JOHN A. OLSON, OF LA GRANGE, ILLINOIS.

DESIGN FOR A CLOTHES-FORK.

SPECIFICATION forming part of Design No. 30,796, dated May 16, 1899.

Application filed April 11, 1899. Serial No. 712,669. Term of patent 7 years.

To all whom it may concern:

Be it known that I, JOHN A. OLSON, of La Grange, in the county of Cook and State of Illinois, have invented and produced a new and original Design for a Clothes-Fork, of which the following is a specification, reference being had to the accompanying drawing, forming a part thereof, in which the figure represents a perspective view of a clothes-fork embodying my design.

The design comprises a configuration presenting the appearance of two prongs A and B converging toward each other at an acute angle and merging into the shank or handle

C, the latter appearing with its sides tapering in line with the outer edge of the respective prongs.

The design further comprises a division-line c, appearing along the longitudinal center of the handle C throughout the length thereof.

I claim—

The design for a clothes-fork, herein shown and described.

JOHN A. OLSON.
